W. Y. DEAR & E. S. COLE.
PROTECTIVE DEVICE FOR PRINTING PRESSES OR THE LIKE.
APPLICATION FILED JULY 11, 1911.

Patented Aug. 26, 1913.

UNITED STATES PATENT OFFICE.

WILLIAM Y. DEAR AND EDWIN S. COLE, OF JERSEY CITY, NEW JERSEY, ASSIGNEES TO
THE JERSEY CITY PRINTING COMPANY, OF JERSEY CITY, NEW JERSEY, A CORPO-
RATION OF NEW JERSEY.

PROTECTIVE DEVICE FOR PRINTING-PRESSES OR THE LIKE.

1,071,608.

Specification of Letters Patent. Patented Aug. 26, 1913.

Application filed July 11, 1911. Serial No. 637,913.

To all whom it may concern:

Be it known that we, WILLIAM Y. DEAR and EDWIN S. COLE, citizens of the United States, residing in the city of Jersey City, county of Hudson, and State of New Jersey, have invented certain new and useful Improvements in Protective Devices for Printing-Presses or the Like, of which the following is a specification.

10 Our invention relates to mechanism for protecting printing presses or like apparatus through which a continuous ribbon of material passes, from injury due to the breaking of such ribbon, and also for minimizing the damage to the ribbon when such a break occurs.

Our improved device is particularly applicable to such portions of printing presses or the like where the paper or other material fed through the machine passes between rollers in juxtaposition or between guides and rollers.

In printing presses it is not unusual to have the paper break after being threaded 25 through the press, and the press started, thus causing a loss in time while the paper is re-threaded and a further loss of material due to the fact that the press continues to operate, and, during such further operation destroys fresh material which would have been saved had the press been stopped at the 30 moment the break in the paper occurred. The greatest likelihood of damage, however, arises from the fact that where the paper passes between two adjacent rollers or between a guide and a roller, and a break occurs, the paper will not continue on smoothly 35 as before between the rollers or between the guide and adjacent roller, but will bunch up between the two surfaces, forming a compressed mass of paper which is finally seized by the revolving rollers and carried between them or between the roller and guide with disastrous results to the machinery, frequently causing the cracking of the 40 rollers or guides or of the shafts of the rollers or bearings in which they rotate.

Our invention is designed to effect the 45 quick stoppage of the press upon the occurrence of an accident of this nature, thus not only preventing damage to the stock being

fed through the machine, but also doing away with any possibility of serious injury to the mechanical parts of the press.

In the accompanying drawings which 55 form a part of this specification, Figure 1 is a side elevation of our improved device showing the parts in the position which they assume when the paper breaks and bunches between rollers or guides; Fig. 2 is a dia- 60 grammatic view of a portion of the printing press showing our improved apparatus applied thereto, and illustrating the electrical circuits which are utilized for the purpose of stopping the press when the paper breaks. 65

Referring to the drawings in detail, the numeral 1 designates a rod forming an integral part of the machine, upon which is mounted a guide 2. A similar rod 3 carries the guide 4, and between these two 70 guides the paper 5 is fed. The paper is shown as being fed from a plurality of feeding rollers, from whence it passes between the longitudinal cutting cylinders 6, thence through the guide rollers 7 and the guides 75 2 and 4 to the collecting cylinder 8, from which it is led to the jaw cylinder 9, the endless belt 10 being provided for causing the paper to aline itself properly upon the collecting cylinder. Mounted upon the 80 rod 1 is a split block 11 of any suitable material which is a conductor of electricity, the two halves of the block being clamped to the rod by means of the screws 12, or in any other suitable manner. Hinged at 13 to the 85 projecting arm 14 of the lower half of the block is a contact strip 15 of any suitable material which is a conductor of electricity. The other extremity of this contact strip is formed into a hook 16 and the parts are so 90 arranged with respect to each other that gravity will normally cause the strip to fall into the position indicated by the dotted lines in Fig. 1, the end of the hook 16 engaging the arm 17 on the other end of the 95 lower portion of the split block. When the contact strip is in this position, sufficient space is provided between the lower surface of the strip and the upper surface of the lower guide 4 to permit the passage of the 100 paper therebetween.

If for any reason the paper breaks in the

vicinity of the guides 2 and 4, it will tend to bunch up, as indicated at 18 in Fig. 1, owing to the fact that the tension in the paper is released, and the paper no longer induced to pass smoothly between the rollers. This clogging of the paper will force the contact strip upward and into contact with a strip 19 of brass or other suitable electrical conductor, which is secured to the lower half of the split block by means of the screw 20, the washer 21 and bushing 22 of fiber, or other insulator, being provided for preventing electrical contact between the strip 19 and the lower half of the block.

When the paper breaks and bunches up, as indicated in Fig. 1, it closes an electrical circuit through contact strip 15, strip 19, wire 23, solenoid 24, or other device for closing a secondary electric circuit 25, 26; wire 27, battery or other source of electro-motive force 28, wire 29, lamp 30, wire 31 and block 11, which is in electrical contact with the contact strip 15 through the hinge 13. The closing of this circuit causes the lamp 30 to light, and through the action of the solenoid 24, or other suitable mechanism, causes a change in the condition of the secondary or auxiliary electric circuit 25, 26, which is connected with any standard type of press stopping device, and thus causes the press to stop. Such devices are well known in the art and it is not considered necessary to describe their operation here. It is obvious that the stop mechanism may be caused to operate either by the opening of the circuit 25, 26 or by the closing thereof, the result, the stopping of the press, being the same in either case.

Since in a large press such, for example, as that used for newspaper work there may be many points at which the paper is likely to break, and since it is desirable to stop the press upon the immediate breaking of the paper, the press may be equipped with a number of protective devices connected in parallel across the circuit, as illustrated by the wire 32, connected to the main circuit at 33, and the wire 34 connected to the main circuit at 35. A tell-tale lamp 36 is connected in each of such auxiliary circuits for the purpose of indicating at once to the press operator where the trouble lies. It will be seen that in case any one of the protective devices operates the press will stop, but only the particular tell-tale light in the circuit of that device will light. The trouble may thus be remedied at once without loss of time in searching for the break in the paper.

While we have described the application of our device to a printing press, it will be obvious that such a protective mechanism will be useful in combination with many other machines in which a flexible material fed therethrough is liable to breakage. We therefore do not wish to be limited to the ap-

plication shown, nor to the particular form illustrated and described.

Having thus described our invention, we claim:

1. A stop device for printing presses or the like comprising a supporting block mounted adjacent to guides through which the material fed through the press is led, an arm hinged at one side of said block and capable of pivotal movement in a plane substantially perpendicular to the surface of said material, an abutting shoulder on said block, a hook on the free end of said arm held by gravity in normal contact with said shoulder slightly above the surface of said material, an electrical contact on said block, and an electrical contact on said arm adapted to be brought into operative engagement by the oscillation of said arm about its hinge. 70

2. A stop device for printing presses or the like comprising a supporting block mounted adjacent to guides through which the material fed through the press is led, an arm hinged to said support and capable of pivotal movement in a plane substantially perpendicular to the surface of said material, said arm being normally forced by gravity into a position adjacent to said surface, an abutting shoulder on said support, a hook on the free end of said arm engaging said shoulder and thereby limiting the travel of said arm in a direction toward said material, an electrical contact on said block, and a second electrical contact on said arm 90 adapted to engage the first when the arm is 100 displaced from its normal position. 95

3. A protective device for printing presses or the like comprising a supporting block mounted adjacent to guides through which the material fed through the press is led, an arm hinged to said support and forming a portion of an electrical circuit operating a stop mechanism for said press, said arm being capable of movement in a plane substantially perpendicular to the surface of said material, an abutting shoulder, a hook on the free end of said arm adapted to engage said shoulder and normally to be held by gravity against the same in close proximity to the surface of said material, a stationary electrical contact forming a part of said circuit but normally insulated from said arm, the circuit being closed through said contact and said arm when the latter is 110 displaced from its normal position. 115

4. In a web printing press, means for operating a stop device for said press, said means including an electrical circuit for operating said device, a plurality of contact makers connected in shunt across said circuit and mounted on said press at different points in the line of progress of the material fed through the press, each of said devices including an arm capable of move- 125 130

ment controllable by buckling of the material and normally supported in close proximity thereto, said arm forming a part of said shunt circuit, a fixed electrical contact 5 also connected in said circuit and normally insulated from said arm, said arm and contact being so disposed that the displacement of said arm will complete said shunt circuit, and an indicating device in each of said shunt circuits.
